CLAIM

The ornamental design for a tillage sweep, as shown and described.

DESCRIPTION

FIG. 1 is a top, left, rear perspective view of a tillage sweep, showing my new design;

FIG. 2 is a top, right, rear perspective view thereof;

FIG. 3 is a rear bottom perspective view thereof;

FIG. 4 is a front elevational view thereof;

FIG. 5 is a rear elevational view thereof;

FIG. 6 is a right-side elevational view thereof, a left-side elevational view being a mirror image thereof;

FIG. 7 is a top plan view thereof; and,

FIG. 8 is a bottom plan view thereof.

The evenly-broken dash-dot lines in the views illustrate portions of the tillage sweep that form no part of the claimed design. The broken dash-dot lines in the views define peripheral boundaries of the claimed design and form no part of the claimed design.
